Des. 190,607

Patented June 13, 1961

190,607

MULTIPLE COMPLETION VALVE

Marvin H. Grove, 340 Hillside Ave., Piedmont, Calif.

Filed May 8, 1959, Ser. No. 55,775

Term of patent 14 years

(Cl. D78—1)

FIG. 3.

FIGURE 1 is a top plan view of a multiple completion valve showing my new design;

FIGURE 2 is a front elevational view thereof; and

FIGURE 3 is a perspective view thereof as seen from the opposite side of FIGURE 2.

I claim:

The ornamental design for a multiple completion valve, substantially as shown.
